(57) **CLAIM**

We claim the ornamental design for a fragrance injector for use on a furnace plenum, as shown and described.

DESCRIPTION

FIG. 1 is a front, top and side perspective view of the fragrance injector for use on a furnace plenum embodying the design of the present invention.

FIG. 2 is a front elevational view thereof.

FIG. 3 is a rear elevational view thereof.

FIG. 4 is a side elevational view thereof.

FIG. 5 is a side elevational view thereof.

FIG. 6 is a top plan view thereof; and,

FIG. 7 is a bottom plan view thereof.
